UNITED STATES PATENT OFFICE

ROBERT E. BRESSLER, OF HAMMOND, AND DOUGLAS V. MOSES, OF EAST CHICAGO, INDIANA, ASSIGNEES TO GRAVER CORPORATION, OF EAST CHICAGO, INDIANA, A CORPORATION OF ILLINOIS

FILTER TANK

Application filed May 17, 1929. Serial No. 363,803.

This invention relates to filter tanks and the like, and is illustrated herein as embodied in a bottom for such a tank constructed in such a manner as to permit the escape of a liquid therethrough and to prevent the escape of the solid matter of the filter.

It is to be pointed out at this stage that by the term "filter" the applicant has reference to all apparatus for containing a solid substance, or solid particles, through which a liquid is passed. This being so, it is to be understood that the term applies to water softening apparatus in which a fluid is conducted through a mass of material for the purpose of exchanging the base of the fluid for that of the material, and applies likewise to other analogous structures.

In many filter tanks, it is customary to provide a bottom plate with perforations therein and to dispose on top of the plate a number of layers of material decreasing in size upwardly away from the bottom plate. Thus, the layer of material that is in contact with the plate is of sufficient size that the particles thereof cannot pass through the perforations, but it is found that quite often they enter into them and become caught in place by means of the edges of the perforations catching upon the rough corners of the particles, thereby interfering with the flow of the liquid through the perforations. To the end of preventing the particles from catching within the perforations it has heretofore been suggested that baffles be employed for guarding the perforations. The baffles that have heretofore been devised have, however, been open to several objections. In the first place, they, in most instances, interfere with the free distribution of liquid over the bottom plate, and in the second place, they are constructed in such a manner that the size of the perforations, or openings, leading thereto vary and even though the variation is small the result is that the liquid tends to escape through the openings, or perforations, of greater size thereby interfering with the proper distribution of the liquid over the bottom plate.

In view of the foregoing considerations, it is an important object of the present inven-

tion to provide an improved bottom plate having baffles guarding the perforations in such a manner that free and equal distribution of the liquid over the bottom plate may take place. A feature of the invention which is conducive to the accomplishment of the recited object resides in disposing the baffles above the bottom plate in such a manner that the baffles are equally spaced from all of the perforations in the plate. This is accomplished by arranging the perforations in rows and providing a single baffle for each row and in supporting the baffle at sufficient points throughout its length that it will at all times remain properly and evenly spaced from the perforations which it guards. Another feature of the invention consists in mounting the baffle in such a manner that free flow of the liquid in all directions toward and away from the perforations, is procured. A still further feature of the invention consists in providing perforations in the bottom plate of a certain size, which, coupled with the baffle construction, is most conducive to proper distribution of the liquid with relation to the bottom plate.

Other objects and features of the invention will become apparent from a reading of the following specification in the light of the accompanying drawings, in which—

Figure 1 is a view partly in section of a filter tank constructed in accordance with the present invention;

Figure 2 is a plan view in section of the apparatus shown in Figure 1 with the filtering substance removed therefrom; and

Figures 3, 4 and 5 are views which show different manners of supporting the baffle strips upon the bottom plate.

Turning now to the drawings, the reference numeral 10 indicates the cylindrical shell of a water softener which comprises a bottom plate 12 having a plurality of layers *a b* and *c* of material, one of which is generally zeolites, disposed thereon in such a manner that the size of the particles in the different layers decreases upwardly. There is provided an inlet 14 through which water enters the bottom of the tank and flows upwardly thru the zeolite material to exit finally through the out-

let 16. The successful operation of such softeners is dependent, to a large extent, upon the proper operation of the bottom, or strainer plate, 12, and to the method of supporting the softening mineral thereon and distributing the incoming water completely through the strainer plate in order that the water will flow upwardly through all parts of the softening mineral instead of being concentrated in certain localities.

The strainer plate 12 is supported by resting it in the annular recess formed at the junction of the bottom 18 of the tank with an upwardly extending flange portion 20 thereof, and is welded to the shell throughout its entire circumference. The perforations in the strainer consist of circular holes and it has been found by repeated experiment that a more proper and uniform distribution 25 of the fluid throughout the softening mineral may be obtained by placing these holes on four-inch centers and making them less than one-half inch in diameter, it having been found that nine thirty-seconds inch orifices 30 are extremely efficient. Thus, the water entering through the inlet pipe 14 flows into the bottom of the tank and engages the under side of the bottom plate whereupon, owing to the size of the orifices therein, the water is 35 distributed over the entire under surface of the bottom plate and passes out approximately uniformly through all of the holes. The water passing through these holes is 40 quickly broken up by the gravel immediately 45 above the plate.

If the gravel, or water softening mineral, were allowed to cover the strainer plate, the perforations would become clogged thereby interfering with the proper distribution and 50 flow of the water through them, and similarly if baffles were provided by securing them adjacent to the openings the free flow of water through openings in the direction of the fastened portion of the baffle would be prevented 55 and the proper distribution would be interfered with accordingly. In view of this, the present invention contemplates constructing the baffles in the manner indicated in Figure 2 in which narrow elongated strips 22 are arranged parallel to one another and cover all 60 of the perforations in the bottom plate. These strips may be supported at their ends 24, as shown in Figure 4, or by means of supporting blocks 26. Figure 3, arranged beneath adjacent baffles, or more preferably by pressing out portions 28, as shown in Figure 5, and utilizing these portions as supports for the baffles. When the baffles are supported in this manner, the fluid passing through the 65 orifices from below may flow horizontally in all directions therefrom, thereby obtaining proper distribution, and furthermore the baffles allow unimpeded longitudinal flow in the clear space beneath the baffle plates which 70 results in added uniformity of distribution

of the flow of liquid into the so-called dead areas between the openings in the perforated plates. If the gravel closes off half the flow space at the edge of the baffle, the full quantity of water flowing through the apertures 75 of plate 12 may still flow freely through the remaining half of the flow space under the edges. In other words, the flow area under the edges is more than twice as great as the flow area of the holes, as clearly seen from 75 the drawings. As a matter of fact, the flow area at the edges is much larger than necessary, with the result that the flow is controlled solely by the size of the hole (for a given pressure) and as the holes are all the same size the 80 flow through all of them is equal, in spite of inequality of blocking off by the gravel. This oversize outer flow area permits the use of a smaller size and quantity of gravel. This, in turn, has the advantage of spreading the 85 flow more uniformly along the edge of the baffle strip.

Although the invention has been illustrated and described herein with particular reference to filters of the water softening type, it 90 is to be clearly understood that the invention is applicable to filters of other types for performing other operations, and furthermore, it is to be understood that from time to time certain changes and modifications in the design and construction in the illustrated embodiment may be made without departing 95 from the scope of the invention as set forth in the appended claims.

Having thus described our invention what 100 we claim as new and desire to secure by United States Letters Patent, is:

1. A filter tank, or the like, comprising, in combination, a substantially flat bottom plate having a plurality of openings formed 105 therein and a plurality of shielding baffles each arranged to guard a plurality of openings, said baffles comprising narrow elongated strips having depressed portions that are of a height proper to serve both as spacing and supporting members, and that are located at points substantially removed from 110 said openings.

2. A tank for filters and the like comprising a bottom plate having a flat upper surface and having apertures therethrough, each of said apertures being covered by a shielding baffle plate spaced therefrom and extending laterally beyond said openings on 115 all sides, the spaces between said baffle plates and said bottom plates being unobstructed in the vicinity of said apertures.

3. A tank for filters and the like comprising a bottom plate having a flat upper surface and having apertures therethrough, each of said apertures being covered by a shielding baffle plate spaced therefrom and extending laterally beyond said openings in nearly 120 all directions to such an extent that the available flow area under the edge of the 125

baffle plate is at least twice as large as the minimum flow area through and adjacent to the apertures, the spaces between said baffle plates and said bottom plates being unobstructed in the vicinity of said apertures and the flow area under the said plate at the circumference of said aperture being equal to the flow area through said aperture.

4. A tank for filters and the like comprising in combination a bottom plate having a flat upper surface and a plurality of aligned apertures therethrough, and an elongated shielding baffle strip covering said apertures, said baffle strip being spaced from the portions of said bottom plate surrounding said apertures and extending laterally beyond each of said several apertures on all sides.

5. A tank for filters and the like comprising in combination a bottom plate having a flat upper surface and a plurality of aligned small apertures of equal size therethrough, and an elongated shielding baffle strip covering said apertures, said baffle strip being wider than said apertures and having depressed portions spaced from said apertures and of a proper height for spacing said baffle strip from said bottom plate, the relative size of the baffle strip and the apertures being such that the available flow area under the edge of the baffle plate is at least twice as large as the minimum flow area through and adjacent to the apertures.

Signed at East Chicago, Indiana, this 9th day of May, 1929.

ROBERT E. BRESSLER.
DOUGLAS V. MOSES.
